UNITED STATES PATENT OFFICE.

JOHN STANLEY HAZELL, OF FOREST GATE, LONDON, ENGLAND, ASSIGNOR TO
UNCHOKEABLE PUMP LIMITED, OF LONDON, ENGLAND.

CENTRIFUGAL PUMP.

Application filed March 16, 1921. Serial No. 452,799.

To all whom it may concern:

Be it known that I, JOHN STANLEY HAZELL, a subject of the King of Great Britain, residing in Forest Gate, London, England, have invented certain new and useful Improvements in and Relating to Centrifugal Pumps, of which the following is a specification.

This invention relates to centrifugal pumps in which the impeller is provided with a single port or passage, through which the liquid is drawn and passes to the discharge.

It will be obvious under these circumstances that when working there will be upon the discharge side of the impeller a body of water the weight of which will act to destroy the balance of said impeller.

The present invention has for its object to provide means designed to overcome this disadvantage and to secure the proper balancing of the impeller whereby the strains which would otherwise be set up upon the impeller and upon the shaft and bearing thereof are avoided.

According to this invention the impeller is provided with a closed chamber so placed and of such dimensions as to permit it to contain a body of liquid of such weight as to secure the balance of the impeller.

In order that the invention may be the better understood drawings are appended in which:—

Fig. 1 is a vertical section longitudinally of the shaft of a centrifugal pump embodying the present invention,

Fig. 2 is a section to a larger scale on line A A Fig. 1.

Referring to the accompanying drawings a indicates the pump casing provided on each side with covers b, b¹ one of said covers b being open for the entry of the liquid. The impeller d, to which is secured in any convenient manner the inner end of the spindle c, is provided with a passage or port d¹ one end of which communicates with the entry or suction whilst the other communicates with the discharge.

The body of the impeller is formed hollow as shown, the hollow portion thereof being provided with partitions e, e¹ divid-

ing the said space into three compartments of which f, f¹ contain air whilst the third f² is designed to contain water the emptying and filling of said chamber being effected by the plug g.

The chamber f² is disposed diametrically opposite to the discharge end of the aforesaid passage or port d¹ its dimensions being so selected that its capacity is such that when filled with liquid the weight of said liquid will be equal to the otherwise unbalanced body of liquid in the aforesaid passage or port. By this means the strains which would otherwise be set up in the impeller, causing unequal wear of the bearings for the impeller shaft, are avoided.

Claims:

1. A centrifugal pump comprising an outer case, an inlet to said case, an outlet from said case, an impeller having a single passage, means for ensuring the balance of the impeller when in operation, comprising a closed chamber formed in the body of the impeller, an opening for filling said chamber and a closure for said opening.

2. A centrifugal pump comprising an outer case, an inlet to said case, an outlet from said case, an impeller having a single passage, means for ensuring the balance of the impeller when in operation comprising a closed chamber formed in the body of the impeller, an opening for filling said chamber and a closure for said opening, the dimensions of the chamber being such that it may contain sufficient liquid to secure the balance of the impeller.

3. A centrifugal pump comprising an outer case having an inlet and an outlet; and an impeller in said case having a single passage provided with means for insuring the balance of the impeller when in operation, said means comprising a closed chamber formed in the impeller and having an opening for filling said chamber and a closure for said opening.

In witness whereof I have hereunto set my hand in the presence of two witnesses.

JOHN STANLEY HAZELL.
